(74) Attorney, Agent, or Firm — MALLOY & MALLOY, PL

(57) **CLAIM**

The ornamental design for a radius flow transom water pickup as shown and described.

DESCRIPTION

FIG. 1 is a front perspective view illustrating my design for a radius flow transom water pickup;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the radius flow transom water pickup, but form no part of the claimed design.

1 Claim, 7 Drawing Sheets(56)
